UNITED STATES PATENT OFFICE

154,858

DESIGN FOR A RAZOR BLADE KNIFE

Sidney P. Johnson, Birmingham, Ala.

Application December 8, 1947, Serial No. 143,043

Term of patent 7 years

(Cl. D22—3)

To all whom it may concern:

Be it known that I, Sidney P. Johnson, a citizen of the United States, residing at Birmingham, in the county of Jefferson and State of Alabama, have invented a new, original, and ornamental Design for a Razor Blade Knife, of which the following is a specification, reference being had to the accompanying drawing, forming a part thereof.

Figure 1 is a plan view of a razor blade knife, showing my new design, and

Figure 2 is an inside edge view thereof.

I claim:

The ornamental design for a razor blade knife, as shown.

SIDNEY P. JOHNSON,
